Design of Pat.

William T. Congesshalls' Design for a Cooking Stove.

Patented November 4, 1885.

Dec. 726

William J. Coggeshall, of Fall River, Mass.
Letters Patent No. 426. Dated Sept. 4th 1855.

The schedule referred to in thes Letters Patent and making part of the same

To all persons to whom these presents shall come.

Be it known that I William J. Coggeshall of Fall River in the County of Bristol, and State of Massachusetts, have invented or produced a new and useful design for a Cooking Stove, the same being exhibited in the accompanying drawings (and described in the following specification) Of such drawings

Figure 1. is a perspective view of a stove, the design being shown therein

Figure 2 - is a vertical section of the side plate, cornice, base & main oven door

Figure 3 - is a horizontal section of said side plate oven door and smaller door
below the hearth plate.

The character of the design is developed by the drawing to an extent sufficient to enable an experienced stove pattern maker to fully comprehend and construct it. I will however state that a, a, denote the feet of the stove; b, the base of it, c the side plate: d, the cornice; e the hearth plate. f, the oven door: g, h, i, k, other doors: l, the secondary hearth plate.

The ornamental configuration of the base, cornice and edge of the main hearth constitutes one feature in the design which I consider important

As in regard not only to the peculiar bas relief star ornament or collection of rays applied to each of the lesser doors, but to that figured on the main oven door - such I deem important features of my design.

The bas relief upon each foot a, is also a part of the design the whole combined with the mouldings and panels exhibited in the drawings I claim as of my production and as constituting the design for which I seek a patent not intending to include the lettering in the hearth plate slide.

In testimony whereof I have hereunto set my signature this

2nd 6th 1855.

Twelfth day of March A.D. 1855.
